UNITED STATES PATENT OFFICE.

KATE DAVIS, OF WILKES-BARRE, PENNSYLVANIA.

MASSAGING DEVICE.

No. 927,125.

Specification of Letters Patent.

Patented July 6, 1909.

Application filed April 22, 1908. Serial No. 428,686.

To all whom it may concern:

Be it known that I, KATE DAVIS, a citizen of the United States, residing at Wilkes-Barre, in the county of Luzerne, State of Pennsylvania, have invented certain new and useful Improvements in Massaging Devices; and I do hereby declare the following to be a full, clear, and exact description of the invention, such as will enable others skilled in the art to which it appertains to make and use the same.

The present invention relates to improvements in massaging devices, and it has for its primary object the production of an exceedingly simple, inexpensive and efficient device of that nature including a pair of massaging rollers located within the interior of the cup-shaped body of the device and projecting below the lower edge thereof.

Other objects and advantages will be apparent from the following specification and it will be understood that changes in the specific construction shown and described may be made and that any suitable materials may be used without departing from the spirit of the invention.

In the drawings forming a portion of this specification and in which like numerals of reference indicate similar parts in the several views: Figure 1 is a side elevation of the present invention. Fig. 2 is a bottom plan view. Fig. 3 is a longitudinal section of the invention, taken on the line 3-3 of Fig. 2.

Referring more particularly to the drawings, the present invention is shown as comprising a substantially cup-shaped member 5, elliptical in cross-section and provided with an outwardly flared rim, concaved slightly with respect to its major axis. The upper portion of the member 5 branches into two tubes 7 and 8, which are arranged for the attachment of rubber hose pipes 9 for the passage of liquids to and from the interior of the member. To prevent accidental displacement of the hose pipes, the free end of each tube is provided with a series of threads or ridges, as shown in Fig. 3.

Within the member is disposed a pair of transversely extending pins 10, each of which carries a roller 11 revolvably mounted thereon, and having its periphery extending beyond the rim thereof, so as to engage any surface against which the device is pressed. The rollers above referred to are preferably formed of rubber or similar resilient mate-

rial presenting a frictional surface, though if desired, metal rollers may be substituted therefor. It is to be understood, moreover, that, while in the present instance, the member 5 is shown as provided with two massage rollers, the device is adapted to operate equally well with three or more rollers, or with a single roller.

In use, the device is disposed with its concave surface against the face, or other portion of the body, in which position the rollers engage the skin and will massage the same when the device is moved about. Water, or other fluid, is admitted to the interior of the member 5 through one of the pipes 9, and thus reaches the parts treated, passing off through the other pipe.

What is claimed, is—

1. A massaging device comprising, in combination, a cup-shaped member having fluid inlet and outlet openings formed therein, and a plurality of rollers disposed within the interior of said member and projecting below the lower edge thereof. 80

2. A massaging device comprising, in combination, a cup-shaped member having fluid inlet and outlet openings formed therein, a plurality of pins disposed within the interior of said member in spaced relation to and parallel with each other, and a roller carried by each pin, said rollers projecting below the lower edge of said member. 85

3. A massaging device comprising, in combination, a cup-shaped member, a plurality of pins disposed within the interior thereof, in spaced relation to and parallel with each other, and a roller carried by each pin, said rollers projecting below the lower edge of said member. 90

4. A massaging device comprising, in combination, a cup-shaped member elliptical in cross-section and formed at its lower edge with an outwardly-flared rim concaved with respect to its major axis, a plurality of pins disposed within the interior of said member in spaced relation to and parallel with each other, and a roller carried by each pin, said rollers projecting below the concave portions of said rim. 100

5. A massaging device comprising, in combination, a cup-shaped member elliptical in cross-section and formed at its lower edge with an outwardly-flared rim concaved with respect to its major axis, said member being provided with fluid inlet and outlet openings, a plurality of pins disposed within the

interior of said member in spaced relation to and parallel with each other, and a roller carried by each pin, said rollers projecting below the concave portions of said rim.

5. 6. In combination with a hollow body; means for passing water therethrough; and a series of hard, independently movable members mounted in the outer end of the body and projecting normally beyond the 10 same.

7. In an apparatus of the character specified, the combination of a hollow body portion; means for passing water therethrough; and a protruding member normally extending 15 beyond the outer face of the body, said member being formed of a substantially unyielding substance.

8. In an apparatus of the character specified, the combination of a hollow body; 20 means for passing water therethrough; a fixed supporting rod or bar extending transversely of an opening formed in the outer portion of the body, and a rotatable member mounted upon said rod and normally projecting beyond the face of the body.

25 9. In an apparatus of the character specified, the combination of a hollow body;

means for passing water therethrough; a series of fixed supporting rods carried by the body in the discharge opening for the water 30 formed in the outer end thereof; and a series of rotatable members mounted upon the rods, said members normally projecting to a slight extent beyond the body.

10. In combination with a hollow body; 35 means for passing liquid therethrough; and a series of independently-movable members normally protruding beyond the outer end of the body.

11. In an apparatus of the character specified, the combination of a hollow body portion; means for passing fluid therethrough; and a series of independently-movable members secured in the outer end of the body portion adjacent to the openings formed for 40 the passage of the fluid and normally projecting beyond the body portion.

In testimony whereof, I affix my signature, in presence of two witnesses.

KATE DAVIS.
